(57) **CLAIM**

The ornamental design for a container for beauty and healthcare products as shown and described.

DESCRIPTION

FIG. 1 is a front elevation view of a container for beauty and healthcare products showing my new design, showing only the front-view surfaces for ease of illustration;

FIG. 2 is a left elevation view thereof, showing only the left-view surfaces for ease of illustration;

FIG. 3 is a right elevation view thereof, showing only the right-view surfaces for ease of illustration;

FIG. 4 is a rear elevation view thereof, showing only the rear-view surfaces for ease of illustration;

FIG. 5 is a top plan view thereof, showing only the top-view surfaces for ease of illustration;

FIG. 6 is a bottom plan view thereof, showing only the bottom-view surfaces for ease of illustration; and,

FIG. 7 is a front-right-top perspective view thereof.

1 Claim, 6 Drawing Sheets
